UNITED STATES PATENT OFFICE.

EUCLID P. WORDEN, OF MILWAUKEE, WISCONSIN, ASSIGNOR TO FRED M. PRESCOTT STEAM PUMP COMPANY, OF MILWAUKEE, WISCONSIN, A CORPORATION OF WISCONSIN.

DUPLEX PUMPING-ENGINE.

SPECIFICATION forming part of Letters Patent No. 738,589, dated September 8, 1903.

Application filed March 12, 1903. Serial No. 147,367. (No model.)

To all whom it may concern:

Be it known that I, EUCLID P. WORDEN, a citizen of the United States, residing at Milwaukee, in the county of Milwaukee and State of Wisconsin, have invented certain new and useful Improvements in Duplex Pumping-Engines, of which the following is a specification, reference being had to the accompanying drawings, forming a part thereof.

10 This invention relates particularly to vertical duplex pumping-engines in which the engine-cylinders are arranged side by side above and in line with the pump-cylinders and the piston-rods are connected by a walking-beam by which a like and synchronous movement thereof in opposite directions is insured.

15 The main objects of the invention are to provide for and facilitate the removal of the upper pump-cylinder heads, whereby access is had to the pump plungers or pistons for packing, repairing, or inspecting the same without disturbing the adjustment of the guides for the cross-heads attached to the piston-rods, and generally to improve the construction and operation of this class of engines.

20 It consists in certain novel features of construction and in the peculiar arrangement and combinations of parts hereinafter particularly described, and pointed out in the claims.

25 In the accompanying drawings like letters designate the same parts in the several figures. Figure 1 is a side elevation of a vertical duplex pumping-engine embodying the above-mentioned invention. Fig. 2 is an end elevation of the same, and Figs. 3 and 4 are enlarged detail views of a portion of one of the cross-heads and one of the guides associated therewith, Fig. 3 being a plan view and horizontal section and Fig. 4 being an end elevation of the cross-head and a side elevation of the guide.

30 For the purpose of illustration the invention is shown as applied to a compound vertical air-pump designed for use in connection with a condenser, but it is applicable to other duplex vertical engines in which the two engine-cylinders are arranged side by side above

and in line with the pump-cylinders, and the piston-rods of the two sets of cylinders are connected by a walking-beam. In this class of engines it is usually necessary to repack the pump plungers or pistons quite frequently, 55 and for this reason provision for ready access thereto without disturbing other working parts of the engine is desirable. In this type of engines it is the usual practice to attach the guides for the cross-heads to the heads of 60 the pump-cylinders, so that in order to remove said cylinder-heads it is necessary to detach and remove the guides. This is not only inconvenient, but also necessitates the careful readjustment of the guides every time the 65 pump plungers or pistons are packed, and even with the greatest care in replacing and adjusting the parts the cross-heads are very apt to bind or work imperfectly on the guides. With my improved construction these difficulties and objections are obviated. 70

Referring to the accompanying drawings, *a* and *b* designate high and low pressure steam-cylinders mounted vertically side by side on a horizontal bed-plate *c*, above and in line with vertical pump-cylinders *d d*. The upper heads *e e* of the pump-cylinders are removable and afford access to the pump plungers or pistons. 75

f f are squared or rectangular guides, which 80 are preferably turned down and threaded at their ends and secured by nuts at their upper ends in the bed-plate *c* and at their lower ends in lugs *g g* on opposite sides of the pump-cylinders outside of and independently of 85 their removable upper heads *e*.

h h are cross-heads attached by keys or other suitable means to and coupling the adjacent ends of the associated piston-rods *h* and *i* of the engine and pump-cylinders. The cross-heads are formed with vertically-disposed rectangular recesses opening through their ends, and in these recesses removable bearing-pieces *j j* are adjustably fitted to the guides *f*. These bearing-pieces may be made, as shown 90 in Figs. 3 and 4, wedge-shaped or tapering lengthwise to take up wear and flanged or L-shaped crosswise to fit over the inner corners of the guides, and thus afford end-thrust bearings for the cross-heads. The bearing-pieces 95 100

may be secured in place and adjusted in the cross-heads by means of screws *k k*, threaded in the cross-heads and having heads or collars engaging the ends of the bearing-pieces. The 5 recesses in the ends of the cross-heads for the bearing-pieces are made of sufficient depth to permit the cross-heads when they are detached from the piston-rods and the bearing-pieces are removed to be tilted vertically out 10 of engagement with the guides without disturbing the latter. The cross-heads are connected and like synchronous movement of the piston-rods in opposite directions is insured by a walking-beam, consisting in the 15 present case of a horizontal rocker-shaft *l*, supported at its ends by bearings in uprights *m m* on opposite sides of the engine and provided with two levers *n n*, which are connected by links or stirrups *o o* with the cross-heads *h h* between the piston-rods and guide-bars.

The uprights *m m* are secured at their lower ends to the engine-frame or pump-cylinders between but independently of their removable 25 heads *e e*; and they with the guides *f f* serve to carry the bed-plate *c* with the steam-cylinders and other mechanism mounted thereon.

It is obvious that with my improved construction and arrangement of parts as here- 30 shown and described the heads *e e* of the pump-cylinders may be detached and removed for the purpose of inspecting, packing, or repairing the pump plungers or pistons or for any other purpose and that the 35 cross-heads may be detached from the piston-rods and disengaged from the guide-bars without removing or detaching the guide-bars or disturbing their adjustment.

In place of the bed-plate *c* lugs or flanges 40 may be formed on the engine-cylinders, or they may be provided with any suitable form of base for the attachment of the upper ends of the guides *f* and uprights *m*.

Various modifications in minor details of 45 construction may be made within the scope of my invention.

I claim—

1. In a vertical duplex pumping-engine in which the engine-cylinders are arranged 50 above and in line with the pump-cylinders, the upper heads of which are removable, the combination of cross-heads to which the piston-rods are attached, a walking-beam connecting said cross-heads, and guides for said 55 cross-heads attached at their lower ends to

opposite sides of the pump-cylinders outside and independently of their removable heads, substantially as described.

2. In a vertical duplex pumping-engine having the engine-cylinders arranged above 60 and in line with the pump-cylinders, the upper heads of which are removable, the combination of cross-heads secured to the piston-rods between the engine and pump-cylinders, a walking-beam connected with each cross-head between its center and ends, and vertical guides attached at their lower ends to opposite sides of the pump-cylinders independently of their removable heads and at their upper ends to the base of the engine-cylinders, substantially as described.

3. In a vertical duplex pumping-engine the combination with the engine-cylinders supported above and in line with the pump-cylinders, the upper heads of which are removable, 75 of vertical guides secured at their upper ends to the engine-cylinders and at their lower ends to the pump-cylinders independently of their removable heads, cross-heads attached to the piston-rods and having open recessed 80 ends and bearing-pieces removably fitted therein, the end recesses in said cross-heads being of sufficient depth to permit their removal from said guides without disturbing the latter, and a walking-beam connecting 85 said cross-heads, substantially as described.

4. In a vertical duplex pumping-engine, the combination with the engine-cylinders arranged above and in line with the pump-cylinders which have removable upper heads, of 90 rectangular guides secured at their upper ends to the engine-cylinders and at their lower ends to the pump-cylinders outside of their removable heads, cross-heads attached to and coupling the engine and pump piston-rods and 95 having rectangular recesses opening through their ends, bearing-pieces adjustably fitted in said recesses to said guides and affording when removed, sufficient space between the cross-heads and guides to permit the removal of the cross-heads without disturbing the guides, and a walking-beam connecting said cross-heads, substantially as described.

In witness whereof I hereto affix my signature in presence of two witnesses.

EUCLID P. WORDEN.
